(57) **CLAIM**

The ornamental design for a storage shelf for infant items, as shown and described.

DESCRIPTION

FIG. 1 is a right front perspective of a storage shelf for infant items, showing my new design;

FIG. 2 is a front elevational view, thereof;

FIG. 3 is a side elevational view, thereof, the opposite side elevational view being substantially a mirror image, thereof;

FIG. 4 is a top plan view, thereof;

FIG. 5 is a bottom plan view, thereof; and,

FIG. 6 is a rear elevational view, thereof.

The broken line representations of infant items in FIG. 1 are included solely for illustrative purposes, forming no part of the claimed design.
